DESIGN FOR A SHAVING BRUSH HOLDER

Stephen S. Wallack, New York, N. Y.

Application July 20, 1946, Serial No. 131,782

Term of patent 7 years

(Cl. D4—3)

To all whom it may concern:

Be it known that I, Stephen S. Wallack, a citizen of the United States, residing at the city of New York, in the county of New York and State of New York, have invented a new, original, and ornamental Design for a Shaving Brush Holder, of which the following is a specification, reference being had to the accompanying drawing, forming a part thereof.

In the drawing:

I claim:

The ornamental design for a shaving brush holder, as shown and described.

STEPHEN S. WALLACK.
